Primary Examiner — Darlington Ly*Assistant Examiner* — Daniel J Domino(74) *Attorney, Agent, or Firm* — Im IP Law; C. Andrew Im(57) **CLAIM**

The ornamental design for a display screen portion with graphical user interface, as shown and described.

DESCRIPTION

FIG. 1 is a front view of a display screen portion with graphical user interface showing our new design; and, FIG. 2 is a front view of a second embodiment thereof. The broken lines showing a display screen portion and text elements of the graphical user interface illustrate portions of the article that form no part of the claimed design.
